United States Patent

Des. 237,846
Patented Dec. 2, 1975

237,846

STOOL

Walter Zeischegg, Ulm, Germany, assignor to Hans-Friedrich Hefendehl, Kierspe, Germany

Filed Nov. 21, 1973, Ser. No. 417,748

Claims priority, application Germany May 24, 1973

Term of patent 14 years

Int. Cl. D6—01

U.S. Cl. D6—32

FIG. 1

FIG. 2

FIG. 3

FIG. 4

FIG. 1 is a top plan view of a stool embodying the novel design;

FIG. 2 is a side-elevational view thereof;

FIG. 3 is the opposite side-elevational view thereof; and FIG. 4 is a bottom plan view thereof.

The stool consists of four elements of geometric identical configuration.

I claim:

The ornamental design for a stool, as shown and described.
